[57] CLAIM

The ornamental design for a metal wall stud, as shown and described.

DESCRIPTION

FIG. 1 is a front perspective view of a metal wall stud showing our new design;
FIG. 2 is a rear elevational view thereof;
FIG. 3 is an end view thereof;
FIG. 4 is a bottom plan view thereof;
FIG. 5 is an enlarged sectional view taken on line 5—5 of FIG. 4;
FIG. 6 is a front perspective view of a second embodiment of a metal wall stud;
FIG. 7 is a rear elevational view of the configuration of FIG. 6;
FIG. 8 is an end view thereof; and,
FIG. 9 is a bottom plan view thereof.

The metal wall stud is broken away to indicate indefinite length.
